(57) **CLAIM**

The ornamental design for a wrist watch, as shown and described.

DESCRIPTION

FIG. 1 is a front, bottom and left side perspective view of a wrist watch showing my new design;

FIG. 2 is a rear, top and left side perspective view thereof; FIG. 3 is a front elevational view thereof;

FIG. 4 is a left side elevation of the wrist watch, the right side elevation is the same;

FIG. 5 is a top plan view of the wrist watch, the bottom plan view is the same; and,

FIG. 6 is a rear elevational view thereof.

Some of the hands on the wrist watch are shown in alternate positions in FIG. 3.

1 Claim, 6 Drawing Sheets
